UNITED STATES PATENT OFFICE.

FLOYD E. HARRIS, OF FLINT, MICHIGAN.

HEAT-CONTROLLING APPARATUS.

Application filed October 7, 1925. Serial No. 61,085.

This is an improvement on the device shown in my prior application Serial No. 601,426, filed Nov. 16, 1922, and is also a continuation in part thereof.

5 The improvements consist, among other things, in simplifying the controls for the valves which supply the fuel and air and, second, in providing a novel valve operating mechanism having the advantages herein-
10 after set out.

While the invention may be thus specifically defined it nevertheless possesses broad phases. Thus it embraces automatic means for operating a valve in which with the aid 15 of two motor devices three positions of the valve may be obtained, one of these being a position to which the valve is biased by suitable means such as a spring. The motor devices which I have preferred to use 20 are electromagnets, which, if desired, may be automatically controlled as by a heat controlled device such as a pyrometer, thermostat, or the like. I have also preferably so constructed my assembly that, when de-
25 sired, the tension of the biasing spring may be relieved.

In the actual apparatus I have provided a plurality of valves operated simultaneously by the motor devices for the control of air 30 and fuel. I have also formed my valves of special design so that when supplied with air and fuel from sources such as herein-
35 after described the proportions of the latter will be constant throughout the range of movement of the valves.

Other objects and advantages of the invention are set out in the following specification.

In the drawings:

40 Figure 1 is an end elevation of the control devices;

Figure 2 is a vertical sectional view of the control, parts being shown in section;

Figure 3 is a section on line 3—3 of Figure 2;

Figure 4 is a section on line 4—4 of Figure 2; and

Figure 5 is a developed view of the air valve.

50 The reference character 2 indicates a panel upon which my control devices are mounted. A casting 4 is secured to the panel by means of bolts 6 and is formed to provide a chamber within which is rotatably mounted valve 8 in the form of a hollow cylinder having

slots 10 and 12 therein. The slot 10 is of peculiar design and is adapted to register with port 14 formed in the upper part of the member 4 and supplied with air at constant pressure by pipe 16 which leads from 60 a suitable fan or other source of air pressure. The air entering through pipe 16 passes through port 14, slots 10 and 12, and is conducted to the burner, not shown, by a conduit 18. The slot 10 is preferably of such 65 design that the volume of air passing therethrough varies directly as the degree of rotation of the valve throughout its range of movement. Two factors must be considered in the design of this opening; first, the back 70 pressure and, second, the fact that the opening 14 is of less angular extent than the opening 10. As to the first, the back pressure increases as the valve is opened and consequently the size of the valve opening 75 must increase at a greater rate than the rate of turning of the valve in order to overcome the effect of the back pressure in resisting flow of air. As a consequence, the valve opening must have diverging sides as 80 full open position is approached, as shown in Figure 5. This divergence must also be increased in order to allow for the second factor in design, that is, the fact that the slot 14 is arbitrarily so chosen for convenience as to be of less angular extent than the opening 10. With this construction the volume of air passing through the valve increases at a fixed rate and in direct proportion to the amount of rotation of the 85 valve. As the flow of fuel through the needle valve varies in the same ratio, the proportions of fuel and air remain constant 90 throughout the range of the mechanism.

The slot 10 also preferably subtends a 95 greater angle than that through which the valve may oscillate so that the valve may be adjusted slightly with respect to the fuel valve to vary the proportions of fuel and air without overrunning the ends of the slot. 100 The amount of adjustment permitted is very slight so that while the proportioning of fuel and air is affected the effect is negligible.

To one end of the member 4 is bolted a 105 fitting 20 recessed to provide a chamber 22 for a needle valve 24 on shaft 26. The needle valve cooperates with a seat provided in a cap 28 having threaded engagement with the fitting 20. A conduit 30 supplies 110

fuel, such as oil or gas, to the needle valve and a conduit 32 conducts fuel therefrom to the burner. A pressure regulator may, if desired, be provided along the conduit 30 so that the oil in the conduit is subjected to constant pressure and this pressure is such that it is at all times so much greater than the back pressure built up on the discharge side of the valve that the flow 10 through the needle valve will vary substantially directly with the area of the valve opening throughout the entire range of adjustment and, consequently, directly with the degree of rotation of the valve. Any 15 suitable packing means 34 may be used to prevent the leakage of oil along the shaft 26 into the air valve compartment.

The cylindrical valve 8 is provided at one end with a sleeve portion 36 in which the 20 shaft 26 is journaled. A yoke 38 is adjustably secured to the sleeve 36 by suitable means such as a set screw 40. The yoke 38 carries a pin 42 straddled by a fork member 44 adjustably secured to the shaft 26. By 25 this means the air valve and the fuel valve may be simultaneously adjusted. Projecting upwardly from the yoke 38 is an arm or stud 46 preferably having threaded engagement with the yoke, and to the upper end 30 of which is secured a spring 48 fastened at its other end to a link 50 connected to an operating handle 52. In the position shown in Figure 1 the arrangement of centers of the parts 50 and 52 is such that the spring 35 is held in tensioned position. By moving the lever 52 to the left the tension of the spring may be relieved. This is desirable to permit hand control under certain conditions such as when the furnace is being 40 freshly fired. It also permits the apparatus to be used as a two position control when desired. By means of this spring the yoke 38 and consequently the air and fuel valves are normally held in a mid or half open position. To one end of the yoke 38 is secured a 45 link 54 pivoted to an armature 56 of an electromagnet 58, the other end of the yoke being similarly connected by a link 60 to armature 62 of electromagnet 64. The 50 electromagnets are, for convenience, designed for operation by an alternating current but if desired direct current may be used for their energization. It is now apparent that by actuating the electromagnets 58 or 64 the 55 yoke 38 may be tilted in one direction or the other effecting either an opening or closing of the fuel and air valves. While any suitable means, manual or otherwise, may be used for controlling the electromagnets I 60 have preferred that they be automatically controlled in accordance with the temperature at the burner as in my prior application. I have indicated diagrammatically at 66 a contact drum which may be operated by 65 any suitable thermally controlled means such

as a pyrometer, thermostat, or the like, not shown. This drum preferably carries contacts 68 and 69, the former in electrical connection with electromagnet 58, and the latter in electrical connection with electromagnet 64. A spring contact member or brush 70 bearing on the drum supplies current to either of the electromagnets in accordance with the position of the drum. When the brush bears against the part 72 of the drum 75 the circuit is broken and neither magnet energized. I have also preferably provided in my wiring connections a switch 74 of any preferred design for throwing both magnets out of the circuit, a fuse device 76 and binding posts 77 mounted in a block 78 of insulating material.

While I have preferred to show direct drum control of the electromagnets it is obvious that if it is desired to operate a 85 battery of furnaces under one control thus necessitating the handling of stronger currents it may be desirable to interpose a relay device between the drum and the magnets to reduce the undesirable arcing.

The operation of the device is as follows. When the furnace is started up the drum 66 is in such position that contact 68 engages brush 70, thus supplying current to electromagnet 58, pulling down armature 56 and 95 tilting yoke 38 against the resistance of spring 48 thus swinging the air valve to the full open position and through the connection 42-44 swinging the fuel valve to a corresponding position. The purpose of the connection 42-44 is to allow for possible inaccuracies in alinement of the two valves. When the temperature of the furnace rises the drum rotates to the point where the brush 70 engages the portion 72 of the drum 100 cutting off the current whereupon the spring 48 restores the valves to normal or mid position. In practice the temperature of the furnace is constantly fluctuating when it approaches the temperature at which it is 105 desired that it be maintained so that the valves are at this time moving back and forth between full open and mid position with considerable frequency. As the temperature of the furnace rises the drum 66 is rotated till contact 69 engages brush 70 energizing electromagnet 64 pulling down armature 62 and thus swinging the yoke 38 and consequently the valves to closed position. In practice it is sometimes desirable 110 that they never be completely closed but remain slightly open even in the so-called "closed" position to permit the passage of sufficient combustibles to maintain combustion at the burner. Here again in actual 115 practice the valves are in a more or less constant state of oscillation this time between mid-position and off position. When the materials have been treated and the furnace stands idle the valves will periodically shift 120 125 130

from mid position to off position maintaining the temperature of the furnace at the maximum for which the control is set.

With the valve openings designed as set forth the proportions of fuel and air remain constant throughout the range of adjustment. The purpose of the pressure regulator on the fuel line is to permit the use of a needle valve of simple design having a larger seat and also to obviate the necessity of adjustment of the fuel valve with respect to the needle valve owing to fluctuations in the gravity of the fuel oil, changes of viscosity due to temperature changes of fuel, and varying pressure of both oil and air due to shop conditions. These shifting conditions may be taken care of by changing the adjustment of the pressure regulator thus avoiding changes in settings of the valves themselves.

I claim:

1. In a regulator for a burner of the type to which fuel and air are supplied by separate conduits provided with valves, means for biasing said valves to one position and thermally controlled means for simultaneously moving said valves to another position, said last named means comprising an electromagnet.
2. In a regulator for a burner of the type to which fuel and air are supplied by separate conduits provided with valves, means for biasing said valves to one position and thermally controlled means for moving said valves to a plurality of other positions.
3. The combination as set forth in claim 2, said first named position being a median position.
4. In combination, a burner, a conduit for conducting an element of combustion to said burner, a valve in said conduit, a rock shaft for operating said valves, means for biasing said rock shaft to one position, thermally controlled means for rocking said shaft to other positions.
5. The combination as set forth in claim 4, a conduit for conducting another element of combustion to the burner, a valve in said conduit, one of said valves being mounted on said rock shaft, the other valve having a loose connection therewith.

6. The combination as set forth in claim 4, said last named means comprising electromagnets adapted to rock said shaft.

7. In combination, a burner, a conduit leading an element of combustion to said burner, a valve in said conduits, a rock shaft for operating said valve, a spring secured to said rock shaft and adapted to hold it in one position, electromagnets, said magnets being operatively connected to the opposite arms of the rock shaft, and means for energizing either of said magnets.

8. The combination as set forth in claim 7, said last named means being thermally controlled.

9. The combination as set forth in claim 7, a conduit for conducting another element of combustion to the burner, a valve in said conduit, one of said valves being directly operated by said rock shaft and the other having a loose connection therewith.

10. The combination as set forth in claim 7, means for releasing the tension of said spring.

11. The combination of a conduit, a valve in the conduit, resilient means biasing the valve to one position, and automatically controlled means for moving said valve to other positions.

12. The combination of a burner, a conduit supplying fuel to the burner, a valve in said conduit, resilient means for biasing the valve to one position, and thermally controlled means for moving said valve to other positions.

13. In a fuel burner, the combination of a plurality of coaxially arranged valves, and an operating device for said valves, said operating device having a loose connection with one of said valves to facilitate assembly.

14. The combination of a burner, a conduit for supplying fuel to the burner, a valve in said conduit, a conduit for supplying air to said burner, a valve in said conduit, means for yieldingly holding said valves in one position, an electromagnet for moving said valves to another position, and thermally controlled means for controlling the operation of said magnet.

In testimony whereof I affix my signature.
FLOYD E. HARRIS.
